UNITED STATES PATENT OFFICE.

JULIUS A. HUSSAR, OF CLEVELAND, OHIO.

AUTOMOBILE-RADIATOR.

1,401,604.

Specification of Letters Patent. Patented Dec. 27, 1921.

Application filed March 15, 1920. Serial No. 365,752.

To all whom it may concern:

Be it known that I, JULIUS A. HUSSAR, a citizen of the United States, residing at Cleveland, in the county of Cuyahoga and State of Ohio, have invented a certain new and useful Improvement in Automobile-Radiators, of which the following is a full, clear, and exact description, reference being had to the accompanying drawings.

10 An object of my invention is the provision of an automobile radiator that is simple and economical in construction, light in weight and efficient in use. A more specific object is to provide a radiator that may be constructed of a plurality of identical cellular units, each adapted to be made from a single stamping with one pair of dies.

Each unit of my invention is made by folding onto itself a corrugated and crimped 20 metal strip. When the units are assembled there are at once provided sets of air passages interspersed with water passages. The side walls of the folded strips thus confine a plurality of air ducts on one side and water passageways on the other, each wall being in contact with the air and water. The water passageways are so arranged that they 25 act to retard the flow of water without causing clogging, and the water distribution and flow and the heat radiation are uniform 30 throughout the entire radiator body.

Other features and objects will become more apparent as the description proceeds. The essential characteristics of the invention 35 are summarized in the claims.

A preferred embodiment of my invention is illustrated in the accompanying drawings wherein Figure 1 is a plan of a strip of metal, the proportions of which may be varied 40 as desired, suitable for the construction of one of the cellular units of the radiator; Fig. 2 is a similar view of the strip after passing through the dies; Fig. 3 is an edge view thereof; Fig. 4 is an end elevation of 45 the strip of Fig. 3, bent to form one cellular unit; Fig. 5 is a front view of a radiator constructed from a plurality of cellular units in accordance with my invention; Fig. 6 is a vertical section through the 50 interior of the radiator body, showing the relative arrangement of air and water passageways, and Fig. 7 is an enlarged section taken on the line 7-7 of Fig. 2. Fig. 8 is a cross section of portions of two adjacent units.

55 In the drawings, 10 designates a rectangular strip of thin sheet metal of suitable

width and length which is struck up in a die to form a peculiarly crimped and corrugated wall, and which when subsequently bent into U-shape and secured in such position, constitutes one cellular unit of a radiator. A plurality of such units properly secured together and incased in a suitable housing may constitute a complete radiator.

The stamping operation to which the sheet 60 shown in Fig. 1 is subjected, causes the longitudinal central portion to be corrugated as at 11, which necessarily reduces it in length as clearly illustrated in Fig. 2. The dies are so shaped that the side margins 12 65 are not corrugated, but a perpendicularly creased or folded portion 14, is formed in each margin, instead, preferably of the same depth but slightly out of alinement with the apex of each depression 15 in the central 70 corrugated surface 11. The portions 13, of the margins 12, between each fold 14, are left in the original plane of the sheet which is also occupied by the uppermost elements or apices of the projections 16, which projections alternate with the depressions 15 to 75 constitute the corrugated surface 11.

As shown most clearly in Fig. 7, the sides of the depressions 15, and projections 16, are preferably of unequal length and slope, 80 the sides 19 being shorter and therefore steeper than the sides 18. The sides unite however, in apices constituting fairly sharp 85 right angles to form the corrugated surface.

90 Since the sides 18 and 19 of the intermediate corrugated portion 11 of the strip 10 are planes connected at right angles, the operation of crimping the margins 12 to form the perpendicular creased portions 14 of a depth 95 equal to that of the depressions 15, increases the length of the marginal portions and necessarily stretches the metal forming them. This increase in the combined length of the marginal single portions 13 and folds 14 100 over that of the walls 18 and 19 of the intermediate corrugations is found to be nearly fifty per cent. By thus stretching the metal of the margins to obtain the greater surface necessary to form the rectangular 105 cellular front and rear faces of the radiator, instead of leaving these portions of the original thickness of the strip and caring for the consequent surplus of metal in the intermediate corrugated portion as by crimping, 110 I am enabled to reduce the weight of metal required nearly one-third. This of

course is of two-fold advantage, being desirable in the matter of reducing the initial cost and in the production of a radiator of light weight. The strength of the radiator 5 thus produced moreover remains ample since it will be observed in the finished structure that the marginal portions thus reduced in weight are of double thickness.

The ends of the sheet 10 as stamped after 10 passing through the shaping dies are bent at right angles as shown at 20, which bent portion constitutes one-half of each intermediate folded portion 14. The sheet may be bent back upon itself at the middle fold 14, 15 as shown in Fig. 4, to bring the bent end portions 20, and each pair of folded portions 14 spaced equidistantly from the ends, into abutting engagement. The joints so formed may be secured together as by solder, 20 thus forming a closed cellular unit 25, the perpendicular sheet portions 13 and 14 forming a row of rectangular cells 26. By virtue of the offsetting of the folded portions 14, with respect to the depressions 15, when the 25 former are bent into abutting relation as shown in Fig. 4, the latter are slightly offset as at 28 in Fig. 6, thus providing a continuous zig-zag passageway 29, extending from top to bottom of each unit 25, and opening 30 at front and rear into the cells 26; the cells 26 and passageways 29 constituting air ducts.

It will be seen that units may be formed by placing two of the corrugated strips in facing relation so that the smooth faces of the 35 margin are separated. This construction avoids the necessity of bending over a strip so that the only metal forming operation that would be necessary would be the corrugation of the center portion of the strip and 40 the crimping of the margins.

In Fig. 5 is illustrated a complete radiator comprising a frame 27, having therein a casing 24, containing a plurality of the cellular units 25, secured together side by side as 45 by soldering the adjacent walls 13 together. The assembly of cellular units 25 side by side provides zig-zag passageways 30 between the adjacent exterior corrugated surfaces of the units. These passageways are closed at 50 front and rear by reason of the soldered joints between the walls 13, but open at top and bottom into the casing 24, and constitute water passages, forming a part of the water circulating system of the jacket of the motor, 55 which may be supplied with water through the usual cap 35.

As shown clearly in Fig. 6 the corrugated walls of each unit 25 are out of engagement, by reason of the offsetting at 28 between the 60 adjacent depressions 15 of opposite walls. This construction permits of a continuous air passage from top to bottom of the unit, thus entirely separating the water passages 30 formed between the units. This separation of the walls of the water passages at

all points at once permits of the maximum cooling effect of the air and reduces the danger of bursting on account of freezing.

It will be apparent that the zig-zag water passages 30 and air ducts 26, 29 of the complete radiator are both formed simply by securing together side by side a plurality of cellular units shown in Fig. 4, which in turn are each made by securing in closed loop form, a single stamping shown in Fig. 70 75 2. Both the water and the air are in full and equal contact with the corrugated portions 11, with only one thickness of sheet metal separating them, while the folded portions 14 and intermediate portions 13 form 80 additional means of extraction and radiation of the heat from the water in the passages. The zig-zag water passageways 30, being rightangular, cause the water in its movement to strike the common walls of the 85 water passages and air ducts with considerable impact. This brings the stream by reason of the sharp angular turns into intimate contact with the walls and retards the flow of water without clogging, causing the efficient transmission of its heat to the cooling air passing through the adjacent air passages 29.

In the cellular formation of the radiator produced by the units 25, the folded portions 90 95 14, which form the horizontal sides of the end cells 26 of the air ducts, are in horizontal alinement when the units are assembled, thus providing with the alined double vertical walls 13, a very strong structure of pleasing 100 appearance.

From the foregoing it will be seen I have provided a radiator which may be cheaply manufactured, and which has water passages provided with a maximum of strength 105 and radiating surface, from a minimum of thickness and weight of material.

I claim :

1. In a radiator, a set of cellular units each comprising a strip of sheet metal, with 110 alternate transverse projections and depressions extending longitudinally forming corrugations, the faces of which are of unequal length, whereby said units may be united to form the connected water passageways and 115 means for securing adjacent units together at the face of the radiator.

2. In a radiator, a set of units each comprising a sheet metal member, having its central longitudinal portion provided with flat 120 sided corrugations said sides being of unequal length and its longitudinal margins with flat portions formed to contact with the flat portions of an adjacent unit.

3. A radiator made of cellular units, secured to each other at their front and rear edges and each comprising a strip of sheet metal having transverse projections and depressions of unequal lengths extending alternately throughout the central longitudinal 125 130

- portion of said strip, each longitudinal margin of said strip being provided with perpendicularly projecting creased portions, adapted to aline across the radiator.
5. In a radiator, a cellular unit therefor, comprising a strip of sheet metal, transverse projections and depressions extending alternately throughout the central longitudinal portion of said strip, each longitudinal margin of said strip being provided with perpendicularly projecting creased portions spaced longitudinally of the strip from the apices of the corrugations.
10. A radiator unit comprising a sheet metal stamping, having its central longitudinal portion provided with rightangular corrugations and its longitudinal margins with perpendicular creased portions of equal depth with the corrugations.
15. A radiator unit comprising a strip of sheet metal having along each longitudinal margin a series of equidistant perpendicular creases, said creased portions being of uniform width and depth, and the portion 20 of the sheet between said margins being corrugated the faces of the corrugations being of unequal length.
25. In a radiator, a metal stamping comprising a sheet having a series of substantially right angular corrugations, said corrugations terminating at the longitudinal sides of the sheet in perpendicular folds, corresponding in number in each edge to the 30 number of the portions in the corrugated surface and slightly offset from the apices longitudinally of the sheet, whereby the stamping is adapted to be united with a similar stamping to form water passages.
35. A radiator made of units each comprising a sheet metal strip having its central longitudinal portion provided with uniform transverse angular depressions, and its margins with perpendicular folds or creases extending in the same direction as the depressed portions in the center, said strip being bent back onto itself with its creased portions brought into abutting engagement and means for securing such portions together whereby water and air 40 passages are formed in the radiator.
45. A radiator section comprising a centrally corrugated strip, the margins of said strip being provided with perpendicular creases, the creases being slightly offset laterally with respect to their extent from alternate apices of the corrugated surface, said strip being bent at its middle point back onto itself with the creased portions extending toward and abutting each other, 50 and the depressions in the parallel portions of the corrugated surface extending adjacent and opposite each other to provide a zig-zag passage therebetween.
55. A radiator section comprising a sheet metal stamping having its longitudinal margins provided with a series of uniform equidistant perpendicular folds and the portion of the sheet between the margins provided with alternate depressions and projections extending transversely of the sheet and parallel to said folded portions, the bottoms of the folded portions and the apices of the depressions lying in the same plane but slightly offset laterally from each other, the ends of said sheet terminating in bent portions, each constituting half of one of said folded portions, the sheet being bent back onto itself to bring said end portions into abutting engagement, and means for securing 60 said parts in such position.
65. In a radiator the combination of a plurality of plates having vertical end portions and intermediate right-angular portions bulged zig-zag from said end portions, said end portions having horizontally 70 folded portions slightly offset from the planes of the apices of the angles of said zig-zag portions, said plates being each bent back onto itself and secured in such position, and the series of such bent plates 75 mounted together side by side, the zig-zag portions of each pair of plates being disposed in parallel relation to form water passages and the walls of cellular air passages, said horizontal folded portions forming 80 with the vertical end portions, rectangular ends for said air passages having sides disposed horizontally and vertically in alignment.
85. In a radiator the combination of a plurality of cellular units secured together side by side at the front and rear ends, each unit having vertical end portions and intermediate corrugations, the apices of the corrugations in both walls of each unit lying 90 in the same vertical plane but in staggered relation, whereby each unit comprises a vertical series of connected cells in its intermediate portion, said end portions having alined horizontally folded portions whereby 95 water passages are formed between the cellular units.
100. A radiator unit comprising a strip of sheet metal bent into a rectangular loop, the exterior of the front and rear margins of 105 said loop being smooth, and having perpendicular spacing members extending therefrom and the portion of the strip between said margins being corrugated the apices of said corrugations being offset from 110 the perpendicular folds.
115. In a radiator a plurality of cellular units, each comprising a substantially rectangular strip formed in a closed rectangular loop, the outer periphery of the front 120 and rear margins of said loop being smooth, whereby a series of said units may be secured together side by side at said margins, the intermediate portions of the walls of each loop being formed with inwardly ex- 125
130. A radiator section comprising a sheet metal stamping having its longitudinal margins

tending corrugations having one set of apices flush with said smooth marginal surface, the space within each loop constituting air passages, and the zig-zag openings thus formed between adjacent loops constituting water passages.

15. A radiator unit having front and rear faces comprising a plurality of rectangular cells formed of stretched sheet metal, the 10 intermediate walls of the unit being of metal of normal thickness provided with inwardly extending transverse depressions and spaced apart to form a continuous zig-zag air passage.

15 16. In a radiator, a set of units compris-

ing a sheet metal member having its central portions provided with corrugations and its longitudinal margins with flat portions formed to contact with the flat portions of an adjacent unit, said flat portions extending flush with one of the sets of apices of said corrugations and having perpendicularly bent folds with the other ends flush with the other edges of the corrugations, whereby the units form water and air pas- 20 25 sages.

In testimony whereof, I hereunto affix my signature.

JULIUS A. HUSSAR.
